UNITED STATES PATENT OFFICE.

THOMAS SHIPLEY OF YORK, PENNSYLVANIA.

ICE-MAKING AND REFRIGERATING MACHINERY.

1,079,610.

Specification of Letters Patent.

Patented Nov. 25, 1913.

Application filed October 7, 1918. Serial No. 793,836.

To all whom it may concern:

Be it known that I, THOMAS SHIPLEY, of the city of York, in the county of York and State of Pennsylvania, have invented certain new and useful Improvements in Ice-Making and Refrigerating Machinery, of which the following is a specification.

My invention relates to that class of ice making and refrigerating machinery in which the refrigerant, such as ammonia, is kept in circulation in a pipe circuit including a condenser, to which the ammonia, after having done its work in the refrigerating coil, is returned by means of a compressor, or, as the equivalent of the same in an absorption system, by means of a generator.

My invention refers more particularly to the means for condensing and cooling the ammonia vapor on its way from the compressor, or the generator, as the case may be, to the refrigerating coil, my object being to enhance the efficiency of the condensing means, and at the same time to reduce largely the area of condensing surface required for the purpose.

To this end my invention consists of the parts and combinations which will first be described in connection with the accompanying drawings, and will then be more particularly pointed out in the claim.

In said drawings—Figure 1 is a representation, largely diagrammatic, of an apparatus embodying my invention. The remaining figures show different forms of condensing means which may be used in the system illustrated in Fig. 1. Fig. 2 is a longitudinal vertical section of so much of a "coil" condenser in its preferred form as needed for the purposes of explanation. Fig. 3 is a similar view of a modification. Fig. 4 is a vertical axial section of a "shell" condenser as applied to the invention. In these figures the ammonia gas is introduced at the bottom of the condenser, and there is a return or stand pipe connecting directly the bottom and top of the condenser. Fig. 5 is a longitudinal vertical section of a "coil" condenser similar to Fig. 1, save that the ammonia gas enters at the top instead of at the bottom of the condenser. Fig. 6 is a longitudinal vertical section of still another "coil" condenser of modified form, adapted to the uses of the invention.

Referring now to Fig. 1—A is the condenser for the ammonia. M is a compressor of any suitable type driven in the usual way. N is the freezing tank, in this instance of the "can" type, containing the usual expansion or refrigerating coil N'.

The pipe circuit through which circulates the refrigerant which freezes the water and makes the ice, includes the compressor M, the condenser A, and the refrigerating coil N', and may be traced as follows: Starting from outlet end of condenser A, the pipe 1 leads into the usual receiver R at which point it has a controlling valve x'. Thence the pipe circuit continues through the pipe 2 to and through the refrigerating coil N' in the usual manner, thence out through pipe 3 to inlet side of compressor pump M, whence it is returned under pressure through pipe 4 to the inlet end of the condenser. Pipe 2 is provided with the usual reducing valve y' by means of which is regulated the "back pressure" in that portion of the circuit between the valve y' and the inlet end of compressor M. The ammonia in this portion of the circuit is usually expanded to about fifteen pounds pressure above atmosphere, or thirty pounds absolute pressure, and when thus expanded is at a very low temperature, far below the freezing point. The pipe 4 through which the ammonia gas is returned under pressure to the condenser A, communicates with the lower end of the condenser coil at which point there is an injector nozzle of suitable character, typified at c, through which the gas is discharged into the condenser, and from the part of the condenser, where the condensed liquid ammonia is located, is led a pipe C which enters the lower part of the condenser coil through the injector shell and supplies that portion of the condenser with a body of ammonia liquid into which the ammonia gas from the compressor is injected and is thereby condensed, the liquid into which the entering gas is forced being constantly renewed by a supply drawn from that part of the condenser containing the condensed liquid.

The same scheme is applicable to an "absorber" system as well as to a "compressor" system. In this modification the compressor is cut out, and the pipe circuit, as shown

by dotted lines in Fig. 1, leads from the outlet end of the refrigerating coil to the absorber O, thence through pump P to the generator Q, and thence to the inlet end of the condenser as in the other case. The pressure in the absorber is, say 15 pounds, while the pressure in the generator is much higher, say one hundred and eighty pounds. The strong aqua ammonia in the absorber is the result of the absorption of the ammonia vapor from the refrigerating coil by the weak aqua ammonia in the absorber, and the interposition of the pump P, as well understood, is needed in order to take the strong aqua ammonia through pipe 5 from the low pressure absorber and force it through pipe 6 into the high pressure generator where the ammonia absorbed as aforesaid, or an equivalent amount of it, is driven off and is thence returned as vapor or gas under pressure to the condenser. The weak aqua, resulting from thus driving off the gas, returns through the pipe 7 to the absorber where it is again strengthened as aforesaid. The pump P is needed to maintain the circulation in the "absorption" system just as the compressor pump M is needed to maintain the circulation in the other system.

I proceed to a more detailed description of the condenser and its connections.

Referring now to Fig. 2, the body of the condensing coil, like that of the usual standard condenser, is formed of a pipe which extends continuously without a break in horizontal stretches or lengths A'-A¹⁰, the return bends *a* of this pipe being suitably connected to the straight stretches or lengths (in this instance ten in number) of the pipe. The cooling water used enters the overhead distributing trough X, and through suitable perforations in the bottom of the same is showered down upon the coil below as customary in this style of condenser. The bottom stretch A' is connected directly with the top stretch A¹⁰ by a return pipe C which forms part of the coil. The coil is thus composed in effect of an endless pipe through which the contents of the coil can travel in a closed cycle.

The ammonia gas from the compressor is led to the condenser through the pipe 4, and enters the condensing coil at the bottom. Before entering the coil at this point, I prefer to subject it to a preliminary cooling, and to this end the pipe 4 opens into a preliminary section composed of a pipe coil B of two lengths or stretches, connected at one end by a return bend b', the upper length of B being connected with a short length of pipe c (here shown in the form of a nozzle) which enters the return pipe C at or near the bottom of the same and extends up therein so that its discharge end will be some little distance above the point where the return pipe joins the bottom length A' of the

coil, the nozzle being of sufficiently less diameter than the pipe to leave between the two an annular space somewhat similar to the annular space around the lifting steam nozzle of an injector. Through this annular space the ammonia liquid can pass from the bottom length of the condenser coil into the return pipe. The ammonia gas entering the return pipe C through the injector nozzle c is forced into the body of liquid contained in said pipe.

The valve controlled outlet for the condensed and cooled liquid is indicated at D as located on the second length A³ above the bottom length A' of the coil. It may be located at any desired point on that part of the coil containing the liquid, but in order to take off the liquid where it is coldest, I prefer to place said outlet in this instance as near the bottom as practicable. From outlet D the pipe circuit continues through pipe 1 to receiver R, and thence to and through the refrigerating coil and back to the compressor, as before explained in connection with Fig. 1. The pre-cooler coil B, to which I lay no claim, serves, as in other condensers heretofore in use, to take out the sensible heat of the ammonia gas before it enters the condenser-proper where the principal work of condensation is done. It is not necessary, however, and may be dispensed with, in which event the pipe 4 from the compressor would be connected directly to the inlet nozzle c.

E is a "purge" valve, such as customarily used on ammonia condensers.

Assuming the condensing coil to be supplied with liquid ammonia at the outset, the operation is as follows: The ammonia gas from the compressor M, after passing through the pre-cooler B, enters the return pipe C through the nozzle c from which it is injected into the column of ammonia liquid in the return pipe, the result of thus bringing the gas into contact with the liquid being the condensation of the gas, the heat of which is taken up by the liquid, the work of condensation being effected as soon as actual and complete contact takes place. The effect of the continuing action of the entering jet upon the superincumbent column of ammonia liquid in the return pipe is to set up in the condenser a circulation of the liquid in the direction of the arrows, the liquid passing up through the return pipe over into the top stretch A¹⁰ of the condenser coil whence it passes down in due course to join the body of liquid contained in the lower part of the condenser. The work of condensation is practically complete before the top stretch of the condenser coil is reached, and that coil is used to cool an already condensed gas, instead of being used, as heretofore, first to condense the gas and afterward to cool the resultant product, thus en-

abling me to reduce very materially the area of cooling surface required. The circulation through the condenser coil and return pipe is in practically a closed cycle, in the direction of the arrows, such portion of the liquid contents as attained the level of the valve controlled outlet D being taken off in regulated flow through said outlet D, whence it passes into the pipe circuit, as before explained. The liquid coming over from the return pipe is effectively cooled during its downward passage through the coil, and when it reaches the bottom stretch A', whence is drawn the supply for the return pipe, it is several degrees cooler than the critical temperature due to the pressure within the coil—that critical temperature (the temperature at which the gas liquefies) varying directly, as is well known, with said pressure. The low temperature of this body of its own liquid into which the entering ammonia gas is injected, assists in the work of condensation; and for this reason I prefer to take off the liquid for this purpose through a connection leading directly to the gas injecting point from that part of the condenser containing the coolest liquid ammonia.

The gas injecting nozzle may be located at some other point on the condenser than the pipe C. For example, in Fig. 3 the nozzle c is represented as located in the end of the bottom stretch A' opposite to that from which the return pipe C leads, passing, for this purpose, through a special return bend a' connecting this end of the bottom stretch with the stretch A² next above. The ammonia liquid passes down from above through this bend into the bottom stretch A', there being an annular passage for this purpose between the nozzle and the interior of the condenser pipe. Like letters of reference in Figs. 2 and 3 indicate corresponding parts. The operation of the condenser is the same as that of the condenser in Fig. 2, save that the work of condensation in this case is done mainly, if not entirely, in the bottom stretch A' before the return pipe C is reached. It will be noted that under this arrangement the ammonia gas taken from the refrigerating coil is discharged into the liquid contained in the bottom of the condenser, where the work of condensation takes place, and the resultant is conveyed from that point directly to the top of the condenser, through which it passes down again to the bottom of the condenser to meet the entering gas, the circulation being in practically a closed cycle, with provision for taking off the liquid as it accumulates beyond the volume required for successful operation of the condenser, and returning it to the pipe circuit which includes the compressor and the refrigerating coil, the liquid in the bottom of the condenser into which

the entering gas is forced being constantly renewed by a supply drawn from the liquid contents of the condenser.

The same mode of operation and effect may be had in a "shell" condenser, as will be understood by reference to Fig. 4. In this figure, the body of the condenser, as usual in condensers of this type, is composed of a vertical shell F, closed at each end by a tube head f of suitable known construction, filled with tubes g which extend the length of the shell, suitable water connections being provided, as shown, to maintain a circulation of cooling water through the tubes g, these tubes serving to cool the contents of the tank. The water circulation is indicated by the arrows. From the lower part of the shell, where the ammonia liquid is coolest, is taken out the return pipe C', which extends up to and enters the top of the shell, as shown. Into the lower part of this pipe, through a suitable fitting, enters the nozzle c', through which the ammonia gas from pipe 4 is forced into the body of ammonia liquid with which the return pipe at that point is filled. The action of this nozzle c' is precisely that of the nozzle c in the condenser coil of Fig. 2. Communicating with the bottom and top of the condenser is another vertical pipe h, on which are located the valve controlled liquid ammonia outlet D', corresponding to the outlet D of Fig. 2, and also, if preferred, the purge valve E. The outlet could be connected directly to the shell, but for convenience sake it is located on the pipe h. The level of the ammonia liquid in this form of condenser is indicated at l. The mode of operation of this apparatus is substantially the same as that of the apparatus shown in Fig. 2. The ammonia gas is injected in the return pipe, and the resultant circulates up through the return pipe into the top of the shell, where it meets the cold water tubes g, and passes down to join the body of the liquid ammonia below, the liquid, as it cools, descending to the level where it passes back into the pipe C' again, and the surplus liquid of condensation passing off through the outlet D'. In this form of condenser, the gas jet may be at the top of the return pipe, as indicated by dotted lines in Fig. 4, which represents the nozzle c' as applied to the top instead of the bottom of the return pipe, in position to inject the gas into the pipe in a downward direction. In this event the circulation of the ammonia liquid in the condenser will be in a direction opposite to that indicated by the arrows in Fig. 4, and the supply of fresh cold liquid for the return pipe to meet the entering gas will be drawn from the top instead of from the bottom of the condenser; otherwise the operation will be the same.

A like modification can be made in the "coil" condenser, as indicated in Fig. 5. In

this modification, the gas nozzle c enters a chamber c^2 which communicates with the top stretch A^{12} of the condenser coil, and has in advance of the nozzle, a conical tube 5 c^3 through which the contents of chamber c^2 pass into the return pipe C beyond. The arrangement is similar to the steam nozzle and "combining" tube of an ejector for handling water. The ammonia gas is injected through nozzle c in jet form into the body of liquid in chamber c^2 , and is thereby 10 condensed, the resultant, by the force of the jet, being driven through the combining tube c^3 into the return pipe C below, the liquid in chamber c^2 being constantly renewed by the supply drawn from the top stretch A^{12} of the condenser. The circulation, which is in practically a closed cycle, 15 is from chamber c^2 down through the return pipe C, and thence up through the condenser coil to the point of beginning, with provision, of course, as indicated at D, for taking off the liquid of condensation as it accumulates beyond the volume needed. The 20 outlet D is located on the top stretch A^{12} ; and the liquid is supplied to the chamber c^2 from the same stretch A^{12} , where, under these conditions, the liquid will be coldest. I would say, however, that this supply need 25 not be taken in any case from absolutely the coolest portion of the liquid contents of the reservoir. For example, in the case of the condenser under consideration, it may be taken from any part of the coil containing 30 liquid, preferably where the liquid is still cool, the return pipe being connected to the coil at that point instead of to the topmost stretch, the condenser remaining otherwise unchanged. And I desire to be understood 35 as including any such obvious modification in my claim. It is best, however, in any case, to take the supply of liquid from as near the coldest point in the condenser as practicable, inasmuch as the cooler the body 40 of liquid into which the gas is injected, the more rapid and thorough will be the work of condensation.

In the modification shown in Fig. 6, the condenser is a "coil" condenser. The gas 45 injecting device is similar to that in Fig. 5, comprising the gas nozzle c , the chamber c^2 , and the combining tube c^3 ; and it is applied to one end of the condenser coil, in this instance the lower end of the coil, being 50 connected to the open end of the bottom stretch A' , as shown. The top stretch A^{12} of the coil is connected by the return pipe C with the chamber c^2 of the gas jet device, and through this pipe passes from the top 55 stretch of the condenser coil, where the liquid is coldest, the supply of liquid needed to renew the body of liquid in the chamber c^2 into which the entering gas is injected. In other respects the condenser will be like 60 that in Fig. 5; and I have therefore shown 65

in Fig. 6 only that end of the condenser which differs from Fig. 5. In this modification the liquid, in its circulation from the gas injecting point, passes through the condensing coil before reaching the return pipe, 70 instead of passing through the return pipe before reaching the condensing coil, as in the preceding figures. But in this, as in other modifications previously described, the condenser is one in which the liquid contents may circulate in practically a closed cycle; the gas under pressure from the pipe circuit embracing the condenser, refrigerating coil and compressor, or its equivalent, is injected, at an appropriate point, into the 75 body of liquid contained in said condenser, whereby said gas is condensed, and a circulation of the contents of the condenser is set up in a direction to constantly renew the body of liquid into which the gas is injected 80 with a supply drawn from the part of the condenser containing the liquid ammonia, with provision for taking off the liquid as it accumulates beyond the volume required 85 for successful operation of the condenser 90 and returning it again to the pipe circuit. This I believe to be new with me.

I do not here claim specifically the form of condenser shown in Figs. 2 and 3, and in full lines in Fig. 4, inasmuch as the same 95 is the subject of my application Serial No. 728,577 filed October 30, 1912.

Having described my invention and the manner in which it is or may be carried into practical effect, I state in conclusion that I 100 do not restrict myself to the particular structural details hereinbefore set forth in illustration of my invention, since manifestly the same can be widely varied without departure from the spirit of the invention; but

What I claim herein as new and desire to secure by Letters Patent is as follows:

In a refrigerating or ice making plant in which a refrigerating coil and a condenser 110 are included in a pipe circuit with means for continuously withdrawing the expanded ammonia vapor from the refrigerating coil and returning it as vapor under pressure to the condenser, whence it passes, condensed 115 and cooled, back to the refrigerating coil, the combination of the following members, viz: the refrigerating coil; the condenser; forcing means adapted to draw the ammonia from the refrigerating coil and return it as 120 vapor or gas under pressure to the condenser; the pipe circuit including said refrigerating coil, condenser and forcing means; an inlet nozzle and connections through which the said ammonia gas from 125 said forcing means is discharged under pressure into the condenser; an outlet through which the condensed ammonia liquid passes off into the pipe circuit; located at a point on the condenser which will main- 130

tain at the gas injecting point a body of its own liquid into which the ammonia drawn by the forcing means from the refrigerating coil is injected as gas under pressure, and thereby condensed; and a connection leading directly to the gas injecting point from that part of the condenser containing the condensed liquid, whereby the liquid at the gas injecting point is constantly renewed by a

supply drawn directly from the liquid contents of the condenser, substantially as hereinbefore set forth.

In testimony whereof I affix my signature in presence of two witnesses.

THOMAS SHIPLEY.
